EDWARD SMITH, OF BRADFORD, ENGLAND, ASSIGNOR TO ESMITH LOOM AND FABRIC COMPANY LIMITED, OF BRADFORD, ENGLAND.

LOOM HAVING CARRIER WHICH INSERTS WEFT IN LOOP FORM.

1,410,518.

Specification of Letters Patent. Patented Mar. 21, 1922.

Application filed November 1, 1918. Serial No. 260,641.

To all whom it may concern:

Be it known that I, EDWARD SMITH, a subject of the King of Great Britain, and resident of Bradford, in the county of York, 5 England, have invented a certain new and useful Improvement in Looms Having Carriers Which Insert Weft in Loop Form, of which the following description, having reference to the accompanying sheets of 10 drawings, is a specification.

This invention relates to the type or class of looms wherein a weft carrier propelled or picked in a similar manner to the throwing or projecting of a common shuttle, is made 15 use of, and in which said carrier takes the weft from a supply of weft, on each side of the loom, in looped form through the shed or warp to the opposite side of said loom, and that in alternate succession, thus 20 in each shed of warp two threads or multiples of two threads are at all times inserted. In accordance with my said invention I so construct the weft carrier and the devices for operating in conjunction 25 therewith, that I am enabled to maintain the approximate speed of a plain or common loom and yet supply the weft continuously as aforesaid, while the devices I employ enable me to produce approximately 30 perfect selvedges on both sides of the fabric, and this I effect by arranging the weft carrier to move in two stages for each pick of weft. That is to say the carrier in its first stage is thrown by the picking mechanism 35 and is arrested in an appropriate position relatively with the edge of the warp threads at the opposite side of the loom until the weft that it has supplied is about to be beaten up by the lay, when it is moved 40 a stage further, thus depositing the weft it carries either accurately within the selvedge or as much beyond same as is desired. To disengage the loop of weft from the weft carrier at the completion or just 45 prior to the completion of the movement of said weft carrier through the last stage of its motion at each pick, I employ cutting means mounted within said carrier, together with means for operating same at the exact 50 period or time desired to attain the object stated.

In order that my said invention may be readily understood I have hereunto ap-

pended sheets of drawings illustrative thereof to which by figures and letters reference 55 is made in the following description.

Fig. 1 is a front sectional elevation showing the slay-board of a loom and the parts supporting same together with sufficient of the framework of said loom to illustrate the 60 application of my improved devices.

Fig. 2 is a plan illustrating the slay board and other parts in their approximate positions when about to beat-up the weft.

Fig. 3 is a similar plan to Fig. 2 but illustrates the position of the slay board as when approaching the completion of the beating-up of the weft.

Fig. 4 is an elevation of a portion of a slayboard and reed with my improved weft 70 carrier and other parts in connection therewith as seen from the front of the loom. The end of the carrier to the right is shown in section in order to show the formation of a part hereinafter explained.

Fig. 5 is a sectional end elevation taken on line A B of parts shown by Fig. 4 and as seen in the direction indicated by the arrow a.

Fig. 6 is a plan of the parts shown by 80 Fig. 4, the end of the carrier to the right being again shown in section.

Fig. 7 is a sectional plan of the end to the left on the carrier, and shows the parts therein in altered positions as compared with 85 the positions they occupy in Fig. 6.

Figs. 8 and 9 are plan and elevation respectively showing part of the mechanism used for moving the weft carrier through the last stage of its motion as hereinafter 90 explained.

Figs. 4, 5, 6, 7, 8 and 9 are drawn to an enlarged scale as compared with the other figures.

C¹ indicate the end frames of a loom, 95 D the top rail of said loom, E the breast beam thereof and F the slay-board or lay while G G¹ indicate the lay-swords.

To attain the object of my invention I make use of a weft carrier 2 which, as is 100 shown, is of the character of a common or ordinary shuttle, the same being thrown from end to end of the lay F alternately by the pickers 3 and 3^a as is the shuttle in a common or ordinary loom. Instead of the 105 weft carrier 2 being charged with a bobbin

or cop of weft, in accordance with my invention it is arranged to have at its two extremities hooks or tongues 4 and 4^a each of which extends from near its respective tip 5 or 5^a inwards towards the centre of the carrier, 2, and within a groove 6 formed in said carrier by reason of the upper edges *b* and *c* of said carrier 2 being made to extend beyond the body part thereof.

10 These upper edges *b* and *c* are made to extend higher than the tongues 4 and 4^a so that they will act as shields for said tongues during the time that the carrier 2 is travelling through the shed, thus preventing either 15 of said tongues engaging with or laying hold of any of the warp threads.

These tongues 4 and 4^a reach from their respective tips 5 and 5^a in such a manner as to form a groove 7 or 7^a between them and the body of said tips, thus when any thread is laid hold of by either of the tongues 4 or 4^a, on the moving of the carrier 2 in the proper direction, said thread is drawn down within the groove 7, 7^a as the case may be, 25 that is to say as to whether the carrier 2 is moving in one direction or the other.

The carrier 2 thus constructed is made to travel as before stated from end to end of the lay F, while extending from the hand rail 8 carried by the lay swords G G¹ on each side thereof, are guiding plates 9, 9^a the lower edges of which project downwards towards the shuttle race on the lay F so that as the carrier 2 travels from end to end of 35 same the lower edges of said thread guides 9 and 9^a will enter the groove 6 within said carrier.

The weft threads 10 and 10^a which are supplied at each side of the loom from any 40 source as a bobbin, cop or the like mounted in any appropriate position relatively thereto, are caused to pass through their respective guiding plates, firstly through the guiding eye *d*, down the front of said plates 9, 9^a 45 and through the guiding slot *f* so that they may finally pass beneath the lower edges of their respective plates 9, 9^a, and extend towards the selvedge of the fabric 11 as shown by Fig. 2 by which arrangement on the carrier 2 being thrown or projected across the lay F the tongue 4 or 4^a at one or other end thereof opposite to the leading end of the carrier, will lay hold of said thread by passing over same in the known manner as 50 shown by Fig. 5, thus on the carrier 2 continuing its motion the loop of thread is carried through the warp to the opposite side to that from which it is taken. On the carrier 2 reaching the picker 3 or 3^a it is arrested preferably in position just prior to the tip and its tongue moving beyond the edge of the warp as shown in Fig. 2. This arresting of the carrier 2 in this position is 55 preferably effected by the picker 3 or 3^a being acted upon by its respective outer

end 103 or 103^a of the usual check straps, which has its said ends arranged to take loosely over their respective picker spindles 104 and 104^a to enable same to act in the identical manner to the check strap in a common loom having an ordinary shuttle, although it is obvious that other arresting devices may be made use of to attain the same object. Each of these straps has one of its ends fixed to its adjacent end frame C 75 or C¹ while its other end takes loosely over its picker spindle 104 or 104^a, thus as the lay F moves away from the position of beat-up it stretches the said straps and causes them to move their respective pickers 3 and 3^a, to meet the incoming weft carrier to arrest its motion as is well known. On the lay returning to beat-up the weft the tension on the straps 103 and 103^a is removed by its said advancing movements, thus permitting the carrier 2 to be restarted into motion as is hereinafter explained.

On the carrier 2 having reached its said position, by the lay F continuing its motion to beat up the shot of weft it will carry said carrier 2 so that it will engage with the outer end *g* or *g*¹ of an operating lever 12 or 12^a pivoted upon the framework of the loom at *h*, *h*¹ respectively. The outer ends *g*, *g*¹ of these levers are made to enter their respective slots *k*, *k*¹ which are made through the front walls of the shuttle boxes so that they may extend into a slot 2^a formed in the carrier 2, when said carrier happens to be within its box, thus as the slay board moves forward, the outer surface of the shuttle box fronts 13, 13^a will come in contact with the bowls *m*, *m*¹ pivoted upon said levers 12 and 12^a respectively causing said levers to travel in a longitudinal direction over said shuttle box fronts 13 and 13^a while moving in a direction towards the front of the loom, thus the outer ends *g*, *g*¹ will engage with its respective end of the slot 2^a in the carrier 2 to complete the longitudinal movement of 105 said carrier by forcing it further into its shuttle box thus bringing same clear of the edge of the fabric as desired. As shown by Fig. 3 the tip 5 of the carrier 2 is brought to the edge of the fabric being woven and 110 by said movement into this position the tension of the double thread of weft 10 is maintained while it is being brought into an appropriate relative position with the outer edge or selvedge of the fabric. The receding of the lay after beating up the weft, carries the shuttle boxes and the weft carrier 2 clear of the levers 12 and 12^a so that the pickers 3 and 3^a may then freely actuate 115 said carrier 2. The returning of the levers 12 and 12^a to their normal positions (which position is indicated by Fig. 2) is effected by retracting springs *n* and *n*¹ and these bring the extending arms of the levers 12, 12^a against stop pieces *p* and *p*¹ respectively. 120

In order to relieve the weft carrier 2 of the loop of weft delivered or deposited by it in the shed, provided the loop end of said weft is desired to lie within or closely to the 5 selvedge of the fabric, I mount within each end of the carrier 2 a spring actuated knife 14 and 14^a which normally lie within grooves s, s¹ in the shuttle tips 5 and 5^a. These knives or cutters 14, 14^a are actuated by 10 levers 15, 15^a; pivoted at t and t¹ respectively within the carrier 2, as said carrier 2 is brought towards the front of the loom when beating up the weft (somewhat as shown by Fig. 3) by reason of said lever 15 15 or 15^a coming in contact with the outer end of a spring actuated lever 16^a or with a spring actuated sliding buffer piece 16 as the case may be. As the buffer piece 16 is a mechanical equivalent for the spring actuated lever 16^a, I make use of either device 20 as I may find advantageous. As the lever 16^a is operated by its spring 17^a when it is free it assumes a normal position with its inner arm drawn against a stop piece u¹ as 25 shown by Fig. 2. By the motion of the lay F during the beat-up of the weft causing said levers 15 or 15^a to come in contact with the operating devices 16 and 16^a said levers are caused to oscillate upon their pivots t, 30 t¹ which moves them from their stop pins w, w¹ to cause the cutting edge or end of the respective knife 14, 14^a to travel crosswise the slot 7 (as shown by Fig. 7 or 7^a) within which the weft 10 or 10^a lies, thus severing 35 or cutting said weft and leaving its free ends in proper positions relative to the edge of the fabric as will be understood.

As means for protecting the wooden part 40 of the carrier 2 at the two ends of the slot 2^a therein, against any undue wear by contact with the ends g, g¹ of the operating levers 12, 12^a; I fix metal projecting pieces x, x¹ therein, as shown by Figs. 4 and 6.

When making use of my improved carrier 45 2 and means as hereinbefore described for actuating same in connection with a fast reed loom, I arrange it to be of sufficient length to reach from the edge of the fabric being woven to the interior of the shuttle 50 box so as to operate the swell lever in said shuttle box to raise the stop rod of the loom in manner well known, while at all times and in every class of loom I desire said carrier to be sufficiently long to reach as far within 55 the shuttle box as is required for the motions of the picker to effectively operate same, thus when I have narrower fabrics to weave I preferably make use of a longer carrier instead of making such carrier adjustable or extensible to meet the requirements of broader or narrower fabrics.

When using a fast reed loom, the pressure 60 of the swell-levers through which my weft carrier actuates the stop rod, may be relieved during the picking operations by any

well known devices which are known for relieving the same pressure in a common-shuttle loom.

As is hereinbefore stated instead of making use of two spring actuated levers such 70 as 16^a I may make use of one such lever and a sliding buffer 16 which is held in a forward position under the actions of its spring 17 as is shown to the left of Figs. 2 and 3. 75

The operating levers 12 and 12^a as well as those for actuating the cutter levers 15 and 15^a are made adjustable so that the time of action for completing the longitudinal movement of the weft carrier after each 80 pick may be varied or regulated so as to take place at any desired time after the arrival of said carrier at the side of the loom and prior to the beating in of the weft. The cutting of the weft may also be regulated to take place by the adjustment of the parts operating the levers 15 and 15^a as 85 stated. I make use of any of the well known methods already proposed for supplying the weft threads at the desired tension from 90 each source of supply as will be understood.

When it is desired to form any particular kind of selvedge it is obvious that I may make use of any well known selvedge shedding mechanism for that purpose. 95

In the carrying out of the novel functions to be performed by a weft carrier in accordance with my invention, I have herein described the simplest and, so far as I believe, the best devices for attaining their respective results, but I would have it understood that many and varied modifications of and equivalents for those described may be made use of without departing from the essential features of my invention. 100

Such being the nature and object of my said invention, what I claim is:—

1. In a loom, a weft carrier, pickers for propelling said carrier, tongues near the extremities of said carrier for laying hold of the weft, weft supplying mechanism, means for temporarily arresting the motions of said carrier in a definite position relatively to the edge of the fabric and means for further moving said carrier beyond the edge 110 of said fabric.

2. In a loom, a weft carrier, pickers for propelling said carrier, tongues near the extremities of said carrier for laying hold of the weft, weft supplying devices which enter a groove in the carrier, means for temporarily arresting the motions of said carrier in a definite position relatively to the edge of the fabric and means for further moving said carrier beyond the edge 120 of said fabric.

3. In a loom, a weft carrier, pickers for propelling said carrier, tongues near the extremities of said carrier for laying hold of the weft, cutters mounted upon said car- 130

rier, means for actuating said cutters, weft supplying mechanism, means for temporarily arresting the motions of said carrier in a definite position relatively to the edge of the fabric and means for further moving said carrier beyond the edge of said fabric.

4. In a loom, a weft carrier, pickers for propelling said carrier, tongues near the extremities of said carrier for laying hold of the weft, weft supplying mechanism, means for temporarily arresting the motions of said carrier in a definite position relatively to the edge of the fabric and levers mounted upon the framework of the loom to engage

15 with the carrier and complete its motion.

5. In a loom, a weft carrier, pickers for propelling said carrier, tongues near the extremities of said carrier for laying hold of the weft, weft supplying mechanism, weft

20 cutters mounted on the carrier, resiliently held devices for operating the weft cutters.

6. In a loom, a weft carrier, pickers for propelling said carrier, tongues on said carrier formed to terminate in grooves near the pointed extremities thereof, weft supplying mechanism, means for temporarily arresting the motions of said carrier in a definite position relatively to the edge of the fabric and means for further moving said carrier beyond the edge of said fabric.

7. In a loom, a weft carrier, pickers for propelling said carrier, tongues near the extremities of said carrier for laying hold of the weft, weft supplying mechanism, means for temporarily arresting the motions of said carrier in a definite position relatively to the edge of the fabric and adjustable levers mounted upon the framework of the loom to engage with the carrier and complete its motion.

EDWARD SMITH.
